UNITED STATES PATENT OFFICE.

JAMES F. PIERCE, OF GLYNRICH, DELAWARE, ASSIGNOR TO AMERICAN VULCANIZED FIBRE CO., OF WILMINGTON, DELAWARE, A CORPORATION OF DELAWARE.

ROLLING-MACHINE.

1,289,257.

Specification of Letters Patent. Patented Dec. 31, 1918.

Application filed March 30, 1917. Serial No. 159,767.

To all whom it may concern:

Be it known that I, JAMES F. PIERCE, of Glynrich, in the county of New Castle and State of Delaware, have invented certain new and useful Improvements in Rolling-Machines, whereof the following is a specification, reference being had to the accompanying drawings.

The invention relates more particularly to a rolling machine adapted to exert a rolling and stretching pressure against the outer face of a tube of fiber or similar material mounted on a mandrel.

An object of the invention is to provide a rolling machine of the above character, wherein the rolling pressure may be exerted against the material on the mandrel at opposed points by rolls which are so set as to move the mandrel, together with its enveloping tube, endwise through the machine.

A further object of the invention is to provide a rolling machine of the above character with means for supporting the rolls, which means is so constructed that the rolls may all be simultaneously adjusted toward and from the axis of the mandrel.

These and other objects will in part be obvious, and will in part be hereinafter more fully disclosed.

In the drawings, which show by way of illustration one embodiment of the invention, Figure I, is a side elevation of a machine embodying the improvements.

Fig. II, is an end view of the same, as viewed from the right of Fig. I.

Fig. III, is a vertical longitudinal sectional view through the machine.

Fig. IV, is a transverse sectional view on the line IV—IV, of Fig. III, and

Fig. V, is a horizontal sectional view through the head showing in plan one pair of the adjustable bearings and the roll supported thereby.

The invention consists primarily in a supporting frame on which is mounted the head of the machine. Located within this head and disposed in equal angular positions about the axis of the head, are three pressure rolls which are adapted to exert a surface pressure against the tube which is to be treated in the machine. These rolls which are driven by suitable mechanism are each mounted in bearings which may be adjusted radially of the supporting head, and means

is provided for simultaneously adjusting all of the rolls. The tube to be treated, after passing between the rolls, is received by a guiding member, and the rolls, as they operate upon the tube, not only exert pressure against the same, but feed the tube endwise through the machine.

Referring more in detail to the drawings, the improved rolling machine consists of a supporting frame 1, which may be of any desired construction. Mounted on this supporting frame is head 2, which, as herein shown, is in the form of a bracket 3, having a base 4, secured to the frame by bolts 5. Bolted to bracket 3, is a cylindrical housing 6, said housing being secured by means of bolts 7.

Located centrally within the housing are three rolls 8, 9, and 10, see Figs. III, and IV. Each roll is mounted on a shaft 11, which is supported in two bearings 12, and 13, one at each side of the roll. These bearings are provided with flanges 52, and 53, respectively, and adapted for radial adjustment under the guidance of suitable slideways 54, formed in the housing 6, as best seen in Fig. V. Bearing 12, has a threaded recess 14, formed therein, see Fig. III, and a stud shaft 15, having a right hand threaded end, engaging this opening. Shaft 15, is mounted in the wall of housing 6, and gear pinion 16, is secured to the protruding end thereof. Bearing 13, is also provided with a threaded recess 17, which receives a left hand thread 18, on a companion stud shaft 19. Shaft 19, is mounted in bearing 20, threaded into the wall of cylinder 6, and said shaft carries a gear pinion 21, which meshes with pinion 16. All three rolls 8, 9, and 10, are provided with these connections, and each pinion 21, meshes with a common gear 22, which is in the form of a ring mounted on a shoulder 55, formed on housing 6, and held in place by a cap plate 23. One of shafts 19, is provided with a hand wheel 24. By turning hand wheel 24, the shaft 19, connected thereto is rotated, and this, through pinion 21, rotates gear ring 22, which in turn meshes with the other pinions 21, so that turning of hand wheel 24, results in the simultaneous rotation of all pinions 21. Meshing with each pinion 21, is a pinion 16, mounted on its shaft 15, which is rotated in the opposite direction. The turning of hand wheel 24, therefore, in

100
105

one direction results in rotating shafts 15, and 19, in opposite directions, but since shafts 15, and 19, are provided with right and left hand threads respectively, it also results in 5 shifting bearings 12, and 13, in the same direction radially of the housing and away from its axis, while a turning of the hand wheel in the opposite direction results in a movement of these bearings radially of the 10 housing and toward the axis thereof.

Connected with each roller shaft 11, by a universal joint, is a link 25, which links are in turn connected by similar universal joints with stub shafts 26, each of which carries a 15 gear pinion 27. Pinions 27, mesh with gear wheel 28, integrally formed on sleeve 29, which is mounted in bracket 30, carried by the main frame 1. The stub shafts are also journaled in said bracket 30. Extending 20 through sleeve 29, is a tubular support 31, which is secured to sleeve 29, by means of set-screw 32. The outer end of this tubular support is flared as at 33, so as to form a tapered guiding surface for the tube to be 25 rolled. Sleeve 31, may, however, be replaced by similar sleeves of different bore, so that the machine may be adapted for rolling tubes of various diameters.

In Fig. III, of the drawings, I have shown 30 a mandrel 34, on which a tube 35, has been formed. The mandrel and tube are fed to the rolls through opening 36, in bracket 3. This tube may be made of fiber or similar material, and after drying, adheres very 35 closely to the mandrel. One of the purposes of the present machine is to roll and stretch these fiber tubes on the mandrels in order to facilitate their removal from the same.

In operation, the rolls first are adjusted 40 so that they will contact with the tube on the mandrel, and press against the outer surface thereof at the opposed points. The amount of pressure exerted against the tube is readily determined and varied by the 45 hand wheel 24, which adjusts all of the rolls simultaneously toward and from the center of the housing supporting the rolls. The rolls are rotated by a gear wheel 37, which is splined to the sleeve 29, and meshes with 50 a pinion 38, on a main shaft carrying a pulley 39. After the rolls are put in operation the mandrel and tube are fed to the rolls through opening 36, and after passing 55 through the rolls enter the tubular guide 31, finally passing out through the same. The rolls, as clearly shown in the drawings, are set at an angle and, therefore, their rotation tends to feed the mandrel and tube through the machine and causes their ejection 60 through the tubular guide 31.

While the rolling machine has been described as particularly adapted for rolling fiber tubes formed and dried on steel mandrels to loosen the same from the mandrels, 65 it will be obvious that the machine may be

used for other purposes, and that the details of construction and the arrangements of parts may be varied without departing from the spirit of the invention as set forth in the appended claims.

Having thus described my invention, I claim:

1. In a rolling machine, the combination of a series of opposed pressure rolls, means for rotating said rolls, means for simultaneously adjusting the said rolls toward and from a point centrally disposed relative to the rolls, and a tubular guide disposed beyond the rolls having its axis in line with said central point, whereby a tube passing through the rolls enters said tubular guide, and is guided thereby, said tubular guide having a tapered guiding surface at its end for directing the tube passing through the rolls into said guide. 70 75 80 85

2. In a rolling machine, a plurality of paired bearings, a roll carried by each pair of bearings and located between the same, a shaft for supporting each bearing, said shaft being radially mounted, and means simultaneously rotating said shafts for moving the bearings radially relative to a center common to said rolls. 90

3. In a rolling machine, the combination of a cylindrical housing, a plurality of paired bearings adjustably mounted therein, a roll carried by each pair of bearings and located between the same, a shaft for each bearing, said shafts being radially mounted in said housing and having threaded connections with the bearings, and means for simultaneously rotating said shafts for moving the bearings radially of the housing. 95 100 105

4. In a rolling machine, the combination of a cylindrical housing, a plurality of paired bearings adjustably mounted therein, a roll carried by each pair of bearings and located between the same, a shaft for each bearing, said shafts being radially mounted in said housing and having threaded connections with the bearings, the threads on the shafts of each pair being respectively right and left hand, and means for simultaneously rotating said shafts in opposite directions for moving the bearings radially of the 110 115 120 125 housing.

5. In a rolling machine, the combination of a cylindrical housing, a plurality of paired bearings adjustably mounted therein, a roll carried by each pair of bearings and located between the same, a shaft for each bearing, said shafts being radially mounted in said housing and having threaded connections with the bearings, the threads on the shafts of each pair being respectively right and left hand, a gear mounted on each of said shafts, the gears of the shafts for each pair of bearings intermeshing, whereby rotation of one of said intermeshing gears rotates both shafts of a 130

paired bearing in opposite directions and moves the roll carried thereby radially of the housing.

6. In a rolling machine, the combination of a cylindrical housing, a plurality of paired bearings adjustably mounted therein, a roll carried by each pair of bearings and located between the same, a shaft for each bearing, said shafts being radially mounted in said housing and having threaded connections with the bearings, the threads on the shafts of each pair being respectively right and left hand, a gear mounted on each of said shafts, the gears of the shafts for each pair of bearings intermeshing whereby rotation of one of said intermeshing gears rotates both shafts of a paired bearing in opposite directions, and moves the roll carried thereby radially of the housing, and means for rotating one gear of each pair of intermeshing gears simultaneously.

7. In a rolling machine, the combination of a cylindrical housing, a series of paired bearings adjustably mounted in said housing, a shaft mounted in each pair of bearings, a roll mounted thereon, means for rotating each roll, a pair of shafts for each pair of bearings, said shafts being disposed radially of the cylindrical housing and supporting the bearings, means whereby a rotation of the shaft moves said bearings radially of the cylinder, a gear carried by each shaft mounted externally of the housing, the gears of each pair of shafts meshing with each other, and a common gear meshing with one of said gears of each pair, whereby a movement of said common gear will cause all the shafts to be rotated and the bearings to be simultaneously adjusted toward and from the center of the housing.

8. In a rolling machine, the combination of a cylindrical housing, a plurality of paired bearings adjustably mounted in said housing, a roll carried by each pair of bear-

ings and located between the same, said rolls being equally disposed about a central point, means for simultaneously moving the bearings radially of the housing, and means for rotating the rolls, said means including 50 shafts having universal connections with the shafts of the rolls.

9. A rolling machine, including in combination, a cylindrical supporting housing, a series of paired bearings mounted therein, 55 a roll for each pair of bearings, a shaft carrying the roll and mounted in the bearings, means for rotating said shafts, means for simultaneously adjusting the paired bearings toward and from a point centrally 60 disposed relative to the rolls, said rolls being set at an angle, whereby the rotation of the rolls causes a tube engaged thereby to pass endwise through the machine, and a tubular guide for receiving and guiding 65 said tube.

10. A rolling machine, including in combination, a cylindrical supporting housing; a series of paired bearings mounted therein, a roll for each pair of bearings, a roll shaft 70 carrying the roll, mounted in each pair of bearings, said rolls being set at an angle whereby the rotation of the rolls causes a tube engaged thereby to pass endwise through the machine, a tubular guide for 75 receiving and guiding said tube, means for driving said shafts including a plurality of shafts connected to said roll shafts by universal joints, a gear on each of said shafts, and a common gear mounted on said tubular guide intermeshing with all of said gears.

In testimony whereof, I have hereunto signed my name at Philadelphia, Pennsylvania, this nineteenth day of March, 1917. 85

JAMES F. PIERCE.
